HELICOPTER TOY

Filed Oct. 7, 1931

UNITED STATES PATENT OFFICE

JAKOB HOJNOWSKI, OF NEKOOSA, WISCONSIN

HELICOPTER TOY

Application filed October 7, 1931. Serial No. 567,486.

This invention relates to certain new and useful improvements in helicopter toys.

The primary object of the invention is to provide a wheeled toy in the form of an aeroplane comprising a body portion supported on wheels with an upwardly disposed horizontal helicopter propeller that may be operated by wind for driving the ground wheels and a forwardly positioned propeller. It is 10 a further object of the invention to provide a helicopter toy of the foregoing character wherein a perpendicular shaft extending through the body portion has gear connections with ground wheels and a forwardly 16 positioned propeller with an elastic cord associated with the shaft for rotating the same to impart movement to the toy.

A still further object of the invention is to provide a helicopter toy embodying an 20 upper horizontal propeller and the usual forward propeller with the operating means therefor constructed in a manner to permit operation of either or both of the propellers without producing forward movement of the 25 toy.

With the above and other objects in view that will become apparent as the nature of the invention is better understood, the same 30 consists in the novel form, combination and arrangement of parts hereinafter more fully described, shown in the accompanying drawings and claimed.

In the drawings:—

Figure 1 is a front elevational view of a 35 helicopter toy constructed in accordance with the present invention, the upper helicopter propeller being illustrated as disengaged from driving connection with the driving shaft;

Figure 2 is a side elevational view of the toy showing the elastic cord associated with the drive shaft and with the helicopter propeller being secured to the drive shaft;

Figure 3 is a top plan view of the spider frame carrying the blades of the helicopter propeller with one blade illustrated; and

Figures 4 and 5 show two forms of elastic cord for operating the drive shaft.

Referring more in detail to the accompanying drawings, there is illustrated a helicopter

aeroplane toy comprising a body portion or fuselage 10 carrying forwardly disposed chassis arms 11 for the support of an axle 12 upon which ground wheels 13 are mounted, the skid support for the rear end of the fuselage including an arm 14 journaled in the fuselage and carrying a ground wheel 15, while the link 16 carried by the arm 14 may be horizontally shifted and engaged with the fuselage for changing the position of the skid 60 wheel 15 for purpose of steering the toy.

A vertical shaft 17 is journaled to the fuselage 10 above the axle 12 with the lower end extending below the fuselage and carrying a bevel gear 18 fixed thereto that is in meshing engagement with the bevel gear 19 journaled upon the axle 12. The bevel gear 19 being selectively locked or keyed to the axle 12 by means of the key 20 pivotally mounted upon the axle at one end thereof as at 21, 70 the key being illustrated in its full lines in Figure 1, engaged with the gear 19 for locking the same to the axle while the released position thereof is illustrated by dotted lines.

A shaft 22 extends longitudinally of the 75 forward end of the fuselage, projects from the forward end thereof and carries the usual propeller 23, the rear end of the shaft 22 carrying a bevel gear 24 in meshing engagement with the bevel gear 25 fixed to the shaft 80 17.

The shaft 17 extends above the fuselage and through the spread wing 26 as illustrated and receives upon its terminal upper end a helicopter propeller. The helicopter propeller comprises a central spider frame 27 having an opening 28 therein for rotatable reception upon the upper end of the shaft 17 with radial arms 29 carried by the spider frame and having apertured plate portions 30 85 at their outer ends to facilitate the support of and attachment to the helicopter blades. Each helicopter blade is of V-formation and includes opposed side walls 31 and 32, the wall 32 being of a width substantially twice 95 the width of the wall 31 while curved wind buffer and brace 33 extends between the free edge of the wall 31 and the intermediate portion of the wall 32. The spider frame 27 is retained upon the upper end of the shaft 17 100.

by a securing nut 34 as illustrated in Figures 1 and 2. The shaft 17 for a portion of the length thereof below the bearing for the spider frame is threaded as at 17a and has a nut 35 threaded thereon that is operated by a handle 36, the helicopter propeller being freely journalled upon the upper end of the shaft 17 when the nut 35 is spaced therefrom as illustrated in Figure 1, while the helicopter propeller is locked to the shaft 17 when the nut 35 is engaged with the bearing portion thereof as illustrated in Figure 2.

The operating means for the shaft 17 includes an elastic cord 37 shown in Figures 2 and 5, having a looped portion 38 at each end thereof, one loop 38 being engaged with a hook on the shaft 17 above the wing 26 and protected by a cover plate 39, the elastic cord being then directed rearwardly to a point 20 adjacent the rear end of the fuselage as at 40 to be passed through an opening in the fuselage and forwardly directed with the other looped end thereof engaged with a hook 41 upon the under side of the fuselage adjacent 25 the wheel chassis as illustrated in Figure 2. Another form of elastic cord 37a is illustrated in Figure 4 having flattened ends slotted as at 38a for attachment to the respective hooks upon the shaft 17 and the under side of the 30 fuselage 10.

From the above detailed description of the invention, it is believed that the construction and operation thereof will at once be apparent, it being noted that when the helicopter 35 propeller is locked to the shaft 17 and the bevel gear 19 is locked to the shaft 12, the elastic cord may be placed under tension by rotating the shaft 17 by means of the helicopter propeller with the wheels 13 elevated 40 from the ground and when proper power has been vested in the elastic cord, the aeroplane toy is placed upon the ground with the elastic cord rotating the shaft 17 to operate the forward propeller 23 and the helicopter propeller, the shaft 17 driving the axle 12 and 45 ground wheels 13. The direction of movement of the helicopter toy may be controlled by the rear skid wheel 15. With the helicopter propeller again keyed to the shaft 17, it 50 is possible to effect operation of both the helicopter propeller and the forwardly positioned propeller 23 by use of the elastic cord 37 without forwardly propelling the toy by 55 disengaging the key 20 upon the axle 12 from the bevel gear 19, the result being that the gear 19 freely rotates upon the axle 12 without effecting movement of the ground wheels 13.

60 While there are herein shown and described the preferred embodiments of the invention, it is nevertheless to be understood that minor changes may be made therein without departing from the spirit and scope 65 of the invention as claimed.

I claim:—

1. In a toy aeroplane, a fuselage, an axle and ground wheels carried thereby, a helicopter and forward propeller on the fuselage, power means for operating the propellers and axle, including a shaft extending perpendicularly through the fuselage, an elastic cord anchored at one end to the fuselage and at its other end to the shaft to be wound thereon, the helicopter being journalled on the upper end of the shaft, and a nut threaded on the shaft to be moved into binding engagement with the hub of the helicopter for anchoring the helicopter to the shaft. 70

15 2. In a toy aeroplane, a fuselage, an axle and ground wheels carried thereby, a helicopter and forward propeller on the fuselage, operating means for the propellers selectively engaged with the axle, including a shaft extending preperpendicularly through the 85 fuselage, an elastic cord anchored at one end to the fuselage and at its other end to the shaft to be wound thereon, the helicopter being journalled on the upper end of the shaft, and a nut threaded on the shaft to be moved into the binding engagement with the hub of the helicopter for anchoring the helicopter to the shaft. 90

20 3. In a toy aeroplane, a fuselage, an axle and ground wheels carried thereby, a helicopter and forward propeller on the fuselage, power means for operating the propellers and axle, including a shaft extending perpendicularly through the fuselage, an elastic cord anchored at one end to the fuselage and at its other end to the shaft to be wound thereon, the helicopter being journalled on the upper end of the shaft, means for anchoring the helicopter to the shaft, a bevel gear fixed to the lower end of the shaft, a bevel gear journalled on the axle in mesh therewith, and means for locking the last named gear to the axle. 100

25 4. In a toy aeroplane, a fuselage, an axle and ground wheels carried thereby, a helicopter and forward propeller on the fuselage, operating means for the propellers selectively engaged with the axle, including a shaft extending perpendicularly through the 110 fuselage, an elastic cord anchored at one end to the fuselage and at its other end to the shaft to be wound thereon, the helicopter being journalled on the upper end of the shaft, means for anchoring the helicopter to the shaft, a bevel gear fixed to the lower end of the 115 shaft, a bevel gear journalled on the axle in mesh therewith, and means for locking the last named gear to the axle. 120

30 5. In a toy aeroplane, a fuselage, an axle and ground wheels carried thereby, a helicopter and forward propeller on the fuselage, and power means for operating the propellers and axle, the helicopter propeller including a central spider frame, a propeller blade carried by each spider arm and of spaced 125 130
